UNITED STATES PATENT OFFICE.

CHRISTIAN WILLIAM MEINECKE, OF JERSEY CITY, NEW JERSEY, AND
CHARLES CATLETT, OF STAUNTON, VIRGINIA.

DESIGN FOR A NURSING-NIPPLE.

SPECIFICATION forming part of Design No. 27,170, dated June 8, 1897.

Application filed April 8, 1897. Serial No. 631,326. Term of patent 14 years.

To all whom it may concern:

Be it known that we, CHRISTIAN WILLIAM MEINECKE, residing at Jersey City, in the county of Hudson and State of New Jersey, and CHARLES CATLETT, residing at Staunton, in the county of Augusta and State of Virginia, citizens of the United States, have invented and produced a new and original Design for Nursing-Nipples, of which the following is a specification.

The design consists in a nursing-nipple or nipple for nursing-bottles having a spherical head or mouth containing triangularly arranged perforations and surmounting a neck, which rises from a flaring base.

The design is illustrated in the annexed drawings, in which—

Figure 1 is a plan view of the nipple. Fig. 2 is a sectional view of Fig. 1.
The bead 1 forms the lower edge of a flaring base 1 2. Said base at its upper part connects by contraction 2 6 with a neck 6 3 of

smaller diameter than the base. The neck has a globular or spherical head or mouth-piece 4, which at its upper portion has three points or perforations 5, arranged triangularly or out of alignment with one another.

The design gives a striking and characteristic appearance.

What we claim as new, and desire to secure by Letters Patent, is—

The design for a nipple for nursing-bottles as herein shown and described.

In testimony whereof we have hereunto set our hands in the presence of two subscribing witnesses.

CHRISTIAN WILLIAM MEINECKE.
CHARLES CATLETT.
